LIQUID DISTRIBUTOR

Socrates Baiesi, Buenos Aires, Argentina

Application September 12, 1935, Serial No. 40,281
In Spain September 19, 1934

12 Claims. (Cl. 221—100)

This invention relates to improvements in an apparatus for supplying liquids in predetermined quantities, such as gasoline or filling station pumps or the like, and has for its main object the provision of a new type of apparatus which, due to its excellent constructive and functional features, offers apparent advantages over all other types of apparatus proposed and used heretofore for the same purpose.

10 The invention also contemplates other objects which will be understood from the course of the present specification.

In order that the invention may be more clearly understood and easily carried into practice, same has been illustrated by way of example, in a preferred embodiment, in the accompanying drawings, wherein:—

Figure 1 is a front view of the new type of naphtha filling apparatus, subject of the present invention, partially sectioned through a vertical plane.

Figure 2 is partly a further vertical section of the same apparatus, and partly a side view.

Figure 3 is a vertical section of the device 25 for regulating the alternative admission of naphtha to either of the transparent containers of the apparatus.

Figure 4 is a detail of the governing mechanism of the alternative charge and discharge 30 valves of each of the transparent containers of the apparatus.

Figure 5 is a transversal section of the top portion of the same apparatus, showing the devices for the alternative governing of the charge 35 and discharge valves.

Figure 6 illustrates the manner in which the alternative opening and closing of the discharge valves of each of the transparent containers of the apparatus is produced.

40 Figure 7 is a partial section of one of the transparent containers of the apparatus, illustrating a detail of the device for the overflow of the excess liquid and the expulsion of the air in suspension.

45 Figure 8 is a vertical section of the governing device regulating the operation of the apparatus, according to the amount of liquid to be delivered.

Figure 9 is a front view of the dial and pointer 50 indicating the amount of liquid to be delivered.

Figure 10 is a partial detail of the governing device of the indicator for the amount of liquid.

Figure 11 is a further front view of the same device, with its corresponding operating balance-beam.

Figure 12 is a front view of the jointed balance-beam for reversing the alternative charge valves of either of the transparent containers.

Figure 13 is a front view of the curved disc 5 for governing the valve for the admission of liquid to the transparent containers of the apparatus; and

Figure 14 is a detail of the jack disc forming part of the governing mechanism of the device indicating the amount of liquid.

The same reference characters indicate like parts or elements throughout the different drawings.

In the form of construction illustrated in Figures 1 and 2, the new type of apparatus for delivering liquids, improved according to the present invention, comprises a solid column 1 formed by a galvanized plate casing or the like, the lower part of which rests on a base 2 of cast material suitably molded, the upper portion carrying the member 3, a detail of which may also be seen in Figures 3, 4, 5 and 6. To the upper part of the member 3, is adapted a suitably shaped plate 4, the lower part thereof being covered by a curved sheet 5 of stamped material.

The two glass or crystal casings 6 and 7 constituting the transparent containers, rest on the above-mentioned plate 4, said containers being closed on the upper part thereof by means of two galvanized cast iron plates 8. The assembly formed by said transparent containers 6 and 7 and the plates 8, is covered on top by a stamped cap 9 secured to the plates 8 by means of screws 10, a sheet support 11 acting as a bearing basis for the glass globe 12, also resting on said cap; said globe is internally illuminated by electric lamps, the electric wires thereof passing through an orifice 13, formed in the center of said cap 9.

15 A plate 14 is fixed within the tubular column 1 at a convenient height, said plate serving as a hermetical cover for the tanks 15 and 16 placed next to each other and consisting of galvanized pipes, which are seamless. From the inclined bottom of the tank 15, starts a short tube 17, the lower free end of which, by means of a threaded coupler 18, is coupled to another seamless tube 19, for the return of the liquid to the feeding tank.

20 The flat bottom of the expansion tank 16 is hermetically connected with a pump 20 of quadruple effect, to the admission end of which is fixed a filtering body 21 provided, internally, with discs 22 formed by brass or similar metallic gauze. On the other hand, to the inlet of the body 21, is adjusted the end of a thick seamless

25 tube 23, which tube is connected with the tank 16, and which tube 23 is connected with the tank 15, for the return of the liquid to the feeding tank.

30 The flat bottom of the expansion tank 16 is hermetically connected with a pump 20 of quadruple effect, to the admission end of which is fixed a filtering body 21 provided, internally, with discs 22 formed by brass or similar metallic gauze. On the other hand, to the inlet of the body 21, is adjusted the end of a thick seamless

35 tube 23, which tube is connected with the tank 16, and which tube 23 is connected with the tank 15, for the return of the liquid to the feeding tank.

35 The flat bottom of the expansion tank 16 is hermetically connected with a pump 20 of quadruple effect, to the admission end of which is fixed a filtering body 21 provided, internally, with discs 22 formed by brass or similar metallic gauze. On the other hand, to the inlet of the body 21, is adjusted the end of a thick seamless

40 tube 23, which tube is connected with the tank 16, and which tube 23 is connected with the tank 15, for the return of the liquid to the feeding tank.

45 The flat bottom of the expansion tank 16 is hermetically connected with a pump 20 of quadruple effect, to the admission end of which is fixed a filtering body 21 provided, internally, with discs 22 formed by brass or similar metallic gauze. On the other hand, to the inlet of the body 21, is adjusted the end of a thick seamless

50 tube 23, which tube is connected with the tank 16, and which tube 23 is connected with the tank 15, for the return of the liquid to the feeding tank.

55 The flat bottom of the expansion tank 16 is hermetically connected with a pump 20 of quadruple effect, to the admission end of which is fixed a filtering body 21 provided, internally, with discs 22 formed by brass or similar metallic gauze. On the other hand, to the inlet of the body 21, is adjusted the end of a thick seamless

tube 23, through which the naphtha contained in the underground storage tank is sucked in.

Said pump 20 is manually operated by means of a handle 24 jointed to the axle 25 thereof.

On the other hand, to the outlet of said pump 20 is fixed an elbow tube 26, provided on the upper part thereof with a cap of the same material. A hinged door 27, for access to the interior of the casing 1, is located therein in front of said handle 24.

As may also be seen in Figures 1 and 2, two short thick tubes or pipes 28 start from the upper part of the tank 15, said pipes or tubes having their lower ends screwed to an extension 29 of the plate 14, while their upper ends are screwed to the packing glands 30. In turn, two conduits 31 and 32 start from the lower portion of said extensions 29, the outlets of said conduits being connected to the thick tubes 33 and 34 respectively, which, as may be seen from the details of Figures 4, 5 and 6, communicate, by means of suitably elbowed conduits, with the vertical overflow tubes 35 and 36, arranged within the transparent containers 6 and 7, respectively.

Also, within said tank 15 are arranged two containers 37 and 38 (Fig. 1), of similar features, dimensions and weight, said containers being capable of alternative displacements in a vertical direction with perfectly guided movements. For this purpose, said containers are suspended from the rods 39 and 40, said rods passing through the bushings 30, serving as guides, and sliding freely within the bearings or bushings 41, and being connected with said containers by means of the radial arms 42.

Each of said containers is guided in course of the upward and downward movement thereof by two blades or lugs sliding along two vertical rods 43 bolted to a cross-piece 44, which in turn is rigidly mounted at the end of a central rod 45 screwed by its upper end to a plug 46, integral with the plate 14. On the free end of an extension piece 53, is screwed a valve body 54, the upper portion of which is adjusted in a hermetical manner to the lower end of a tube 55, as may be seen in the detail of Figure 8; said tube 55 is screwed to the lower mouth of a box 56, carrying a further tube 57 which, as will be explained later, communicates in turn with the interior of the device distributing the pumped liquid to each of the transparent containers, as shown in the details of Figures 3 and 5.

Also, within the body 54 are two seat-valves 58 and 59 the first of which, as shown in Figure 2, closes at a given moment the upper or outlet end of the tube 51, while the valve 59 is capable of closing the inlet end of the upper tube 55; this latter valve is controlled by the action of a small jointed balance-beam 60, the operation of which will be explained hereinafter.

As may be seen in Figure 3, within the member 3 shown in Fig. 1, two curved conduits 61 and 62 are formed, which communicate with the tube 57 for the inlet of the liquid, and which are upwardly closed by the conical seat valves 63 and 64 respectively; said valves, on being raised by means which will be explained later, allow the admission of liquid to either of the transparent containers of the apparatus.

In turn, the flat valves 65 and 66 are fitted to the lower mouth of each of the curved conduits 61 and 62, said valves being joined to each other and to the free end of a balance-beam or arm 67, said balance-beam being operated indirectly by the horizontal axle 68. To this effect, said

arm ends in a collar 69 carrying a screw 70 used for the adjustment of the arm 67 on a horizontal bushing 71, arranged within said member 3. As may be seen in the section of Figure 5, said bushing 71 encloses the rotation axle 68, serving as a bearing therefor; both the bushing 71 and the axle 68 operate between two bearings 72 screwed to the external wall and to an intermediate wall or partition of the member 3. As may also be seen in Figure 5, the extreme portion of the bushing 71 encloses a spiral spring 73 which is arranged between said bushing and the corresponding axle thereof, said spring being maintained in a pressed condition by means of a thin annular bushing 74 fitting by its free ends below the piece 71 and under one of the bearings 72. Also, to counteract the lateral pressure of said spring, the external bushing 71 is provided with a conical projection 75 pressing against the bearing 72.

As shown in Figure 6, two valves 76 and 77 of alternative operation are also fitted on the upper plate 4 which, as stated above, closes by its lower part the transparent containers 6 and 7 of the apparatus; the purpose of said valves being to allow the discharge of either of the transparent containers of the apparatus. These valves are actuated upwardly, during their opening movement, by two thin stems or rods 78 jointed to the free ends of two connecting rods 79, each of which is jointed at its intermediate points to two small axles 80 provided with corresponding nuts. Each connecting rod 79 forms at the back end a toothed sector 81 meshing with a small pinion 82 mounted on the axle 68 mentioned above, and which, as may be seen in Figure 5 is held in position by a latch 83. Said pinion 82 is also integral with a small circular sector 84, for the purpose to be explained later.

Figures 5 and 6 also show that the iron balance-beams 85 and 86 have been arranged on the upper portion of the plate 4, said balance-beams being carried at their centers, on the supports 87 fixed to said plate. Each of the free ends of said balance-beams 85 and 86 engages the pairs of valves 76-63 and 77-64 respectively, which consequently are governed by alternative movements, so that while one of them, for example the valve 77 opens to allow the discharge of the transparent container 7, the adjacent valve 64 is pressed against the seat thereof, closing the outlet of the curved conduit 62, as may also be seen in Figure 3.

Also, on the opposite end of the axle 68 the bushing 71 is extended outwardly, as may be seen in Figure 5, carrying fixed thereto, by means of a screw 88, an oscillating support 89, the front detail of which may be seen in Figure 4. This support carries joined thereto in its lower and internal portion, a counterweight 90 which is situated between said piece and the wall of the member 3, while on the upper and external portion of said support is provided a balance-beam 91 rotating around the rotation axle 92. Said balance-beam 91, the front detail of which may also be seen in Figure 4, is provided at its inner portion with an extension capable of fitting in a notch 93 formed in the periphery of the circular sector 94 when the latter is pressed, on its free ends, by a laminar spring 94'. In turn, the circular sector 94 is integral with a toothed wheel 95, as may be seen in the section of Figure 5, which by means of the latch 96 is fixed to the free end of the axle 68.

A short chain 97 meshes with the toothed wheel 75

95, the free ends of said chain being joined to the upper ends of two thin rods 98 (Fig. 12) and 99 which, as may be seen in the details of Figures 2 and 12, are joined in turn to the opposite ends of a balance-beam 100, mounted on a horizontal axle 101 and fixed to the free end of same by means of a latch or bolt 102. This axle, as is more clearly shown in the section of Figure 8, crosses the chamber 56 throughout its width, said 10 chamber being interposed, as stated above, between free ends of the tubes 55 and 57, allowing however, the free communication between both.

In said Figure 8 it may also be seen that said axle 101 is mounted on the box 56 by means of 15 two ball-bearings 103 and 104, the latter being adjusted by means of a small metallic plate or disc 105.

Also, on the same axle 101 is fixed a balance-beam 106, the front detail of which may be seen 20 in Figure 11, said balance-beam ending upwardly in a circular sector 107 acting by pressure against the lower portion of an arm 108, one of the ends of which is joined to the pivot 109 carried by the box 56 (Fig. 8), and the opposite end of 25 which is fixed to a counterweight 110. In its upward and downward movements, said arm 108 is guided between the vertical lugs 111 formed on the inner wall of said box. On the other hand, the counterweight 110 is joined to a rod 112, 30 which as may be seen in Figure 1, is joined to the balance beam 60 which, as already stated, governs the upward and downward movements of the valve 59.

As may be seen in Figure 1, on the free ends 35 of the balance-beam 106 are arranged two thin plates 113 and 114, which by means of the bushings 115 are in turn joined to a suitable point of the vertical rods 116 and 117, said rods being suitably guided for their vertical displacement, 40 by a solid support 118. Said rods 116 and 117 are caused to follow the rods 39 and 40 respectively, with which they form a single piece.

By observing Figures 8, 10 and 11, it will be seen that on the same axle 101 a drum 119 is 45 rotatably mounted, said drum being open at the back and having at its periphery a series of openings or orifices 120, the number of which is equal to the number of five-liter batches which may be effected with a total of fifty liters which 50 is the maximum that may be marked in one delivery.

Within said drum 119 and fixed on the axle 101 is arranged a small gear 121 meshing with a small pinion 122, the axle of rotation 123 of 55 which is carried by a support 124 fixed to the inner portion of the box 56. In turn, said pinion 122, as may be seen in Figure 14, meshes with a toothed sector formed in the inner portion of a disc 125 which, as is illustrated in Figure 8, 60 is freely mounted on the axle 101, being internally guided by an internal cavity of the gear 121. Said disc 125 has joined thereto at an intermediate point, a trigger 126, the purpose of which will be explained later; also in the inner 65 portion of the drum 119 is arranged a further trigger 127 similar to the trigger 126 and arranged in an opposite position to it, said trigger 127 being rotatably mounted upon the front of the sector 107 already mentioned.

70 Also, at one end of the drum 119 is formed a hollow extension in the shape of a tube, against which a further cylindrical bushing 128 is arranged, from which a curved disc 129 starts; the periphery of said disc, as may be seen in the 75 detail of Figure 13, has a projecting tooth 130

and an inwardly extending tooth 131, suitably profiled. On the inner end of the bushing 128 is formed a series of triangular teeth 132 with which a jack 133 meshes (Fig. 18), said jack being joined to the front of the piece 119 and being pressed by a thin laminar spring 134, as may be seen in Figures 10 and 11. Facing said jack 133 is provided a small cylindrical sector 135 which is fixed against the inner portion of the tubular extension by means of a small screw 136. 10

As shown in Figure 8, on the free end of the bushing 128 is screwed a piece 137 which freely passes through a metallic disc 138 fixed on the open front of the box 56. Said piece 137, which is partially hollow, has in the front portion a 15 central perforation to allow the free passage of a detachable key 139 for operating the device indicating the amount of liquid to be delivered.

In the detail of Figure 9, it may also be seen that said key 139 fits between two small jacks 20 140 which are joined to the inner front portion of the piece 137 and which are pressed by two small laminar springs 141.

As also shown in Figure 9, on the front part 25 of the disc or dial 138, the different numbers indicating the amount of liquid to be delivered in each operation have been marked, opposite to which an index or pointer 142 is arranged, said pointer being fixed to the front of the piece 137. Also, on said disc 138, a perforation 143 has been 30 made, through which may be read the numbers of the totalizer 144 (Fig. 8), suitably mounted on a support 145 fixed within the box or casing 56. Said totalizer is operated by a lever 146 which, as may be seen in Figure 10, is joined to 35 the same support 145 and the upper end of of which, ending in the shape of a tooth, fits in the different perforations 120 formed, as already stated, in the periphery of the disc or drum 119.

The device for the expulsion of the air contained in the transparent containers during their filling operation and for the overflow of the excess liquid has been illustrated in Figure 7. Said figure shows the tube 35 which, similarly to the tube 36, reaches to the upper portion of the 40 transparent containers 6 and 7 respectively, 45 which, as already stated, are upwardly closed by the plates 8.

As may be seen, in the upper part of each of 50 said plates 8 is formed a vertical extension 147 which carries in its inner portion a screwed piece 148 which is hermetically adjusted relatively to said plate by means of the packings 149. In turn, on the lower end of said tubular piece is 55 screwed the threaded portion of the tube 35.

Figure 7 also shows that on the sides of the tubular piece 148 are formed a series of rectangular openings 150 which allow the passage of the excess liquid, which will freely empty into said tube 35, as indicated by full line arrows. 60

Within the tubular piece 148 is screwed a plug 151 which also may be adjusted hermetically relatively to the former by means of a packing 152, leaving a small free space on the border of the central tube 35. Within said plug, a cylindrical 65 chamber is formed, said chamber 153 communicating with a small vertical tube 154 fixed on the lower part of same. The central chamber 153 communicates, by means of suitable openings, with two other concentrical chambers 155 and 70 156 formed between the plug 151 and the bushing 128, and between the latter and the extension 147 of the plate 8, respectively. Finally, the external chamber 156 communicates, by means of a thin conduit with a small tube which, as may 75

be seen in Figures 1 and 6, is joined by means of a T-piece, with the similar tube starting from the opposite transparent container, and with an outlet vertical tube 158 reaching to the lower plate 4, to which it is fixed by means of a threaded bushing 159 and counternut 160.

In Figures 5 and 6 it may also be seen that over the front of the member 3 is adapted a piece 161 provided with a small spy-glass or the like 162 through which the outlet of the liquid may be observed, and to the lower portion of which a piece 163 is fixed; a thick tube 164 for the outlet of the liquid starts from said piece 163, said tube having on its free end the corresponding 15 delivering hose screwed to same.

Said piece 163 constitutes the body or chamber of the float; a floating cylinder 165 is fixed on the free end of an arm 166 rotating about a horizontal axle 167. A curved projection 168 is 20 formed on said float, which on being raised from its position by the lifting of said float, acts against the circular sector 84 which, as already stated, is integral with the pinion 82 mentioned above. In its upward and downward movements, 25 the float 165 is guided by two small stems 169 fixed on the inner wall of the member 3.

As may also be seen in Figure 5, the inner portion of the same member 3 has a small steel spring or the like 170 operating by pressure 30 against the free end of the horizontal axle 68, holding same against a seat formed by the projection 75 and bearing 71. At the entrance of 35 the conduit 164 and adjusted by screws or any other means, is a metallic sheet 171 in the shape of a partition, the object of which is to prevent that, from the outside, the arm 166 of the float may be caught, or to prevent any other fraudulent manipulations.

As may be seen in Figures 1 and 2, at one side 40 of the body 54 a plug 172 has been screwed, said plug being provided with a small horizontal perforation from which extends a small thin tube 173 which, as will be seen later, is intended for the return of the liquid left in the transparent 45 containers to the feeding tank. Said tube communicates with a further small tube 174 which, by means of a counternut 175 is coupled to the plug 46 mentioned above, in which a series of 50 small perforations 176 has been made for the overflow of the liquid contained in said tube.

Said tube 174 is in direct communication with the vertical tube 177, which as may also be seen in the detail of Figure 5, presents in its upper part a funnel 178 for collecting the liquid that 55 may have filtered through the valve-axes.

As may be seen in Figure 2, a further small tube 179 empties also into the same plug 46, said tube collecting the liquid which may have filtered through the lower valve device.

Finally, as may be seen in Figure 2, within the tank 16 an overflow tube 180 has been adapted, said tube assuring a constant level of liquid within said tank when the apparatus is not being used. The excess over the level of said liquid 65 returns to the feeding tank by means of the tube 181 communicating directly with the vertical tube 19.

The operation of this type of apparatus is very simple and is effected in the manner explained 70 below:

When the consumer asks for a determined amount of liquid, the operator will be compelled, in order to carry out the pumping, to place the indicating pointer 142 on the division of the disc 75 138 corresponding to the quantity asked for, as is

illustrated in Figure 9. To effect this, he will operate the detachable key 139 which will be placed over the axle 101, as may be seen in Figure 8, and will rotate the piece 137 until said pointer marks on the disc 138 the number of liters desired by the consumer. It will be observed that, on rotating said pointer 142, the curved disc 129 will also rotate, the projecting tooth 130 thereof will lift the arm 108 to which is fixed the counterweight 110 and the rod 112, and this latter rod 10 will in turn cause, as shown in Figure 1, the lowering of the valve 59 by means of the balance-beam 60.

Assuming, for example, that the consumer wants 15 liters, the operator will actuate said key 139 until the pointer 142 coincides with the number indicating this quantity on the disc 138. In effecting this operation he will have caused the rotation of three teeth of the pinion 132, which is equal to three deliveries of five liters. 20 It must also be borne in mind that the jacks 149 only allow the pointer to move forwardly.

If the lever 24 is thereupon actuated, the pump 20 will be operated which, by means of the suction pipe 23, will draw the naphtha from the deposit tank, causing same to pass through the filter 22 which, as already stated, is constituted by two gauzes of different mesh, said filter retaining all the impurities carried by the liquid. By the action of said pump 20, the liquid will 30 then be forced through the pipe 26, emptying into the tank 16 of air displacement.

The liquid entering said tank, will be subjected to a determined pressure by the action of the pump 20, and after displacing the air, will rise, 35 through the action of the same pressure, through the pipe 51, causing the lifting of the corresponding retention valve 58, shown in Figure 2, then passing to the valve body 54. As the valve 59 (see Figure 1) has been lifted in the previous 40 operation, that is to say, when marking the amount of liters to be delivered, the liquid forced by the feeding pump will pass through said valve 59 and rising through the pipes 55 and 57 will reach the valve chamber represented in Figures 45 3 and 5.

Assuming that at this moment the valves 65 and 66 are in the position represented in said Figure 3, that is to say, covering the entrance to the conduit 61, the liquid which has arrived 50 through the pipe 57 will be compelled to rise through the conduit 62, and after lifting the valve 64 will enter the transparent container to be charged, which in this case will be the transparent container 7, the discharge valve 71 of 55 which will be closed, since same, as may be seen in Figure 5, operates in counterposition with said valve 64 by the action of the balance-beam 85.

Now, the liquid entering this transparent container will fill same completely, and the liquid entering later will overflow through the upper part of the central tube 36, as illustrated by the continuous arrows of Figure 7, while the air bubbles carried in suspension by the liquid will 65 escape in the direction of the dotted arrows, being expelled to the exterior after passing through the tubes 157 and 158, shown in Figures 1, 6 and 7, thus obtaining the exact measure of the liquid.

In turn, the liquid which has overflowed to the interior of the central tube 36, will pass through one of the curved conduits represented in Figures 4 and 6, pouring into the tube 34 and after passing through the conduit 32 will empty into the 75

movable container 38, as shown in Figures 1 and 2.

Said container 38 as well as the similar container 37 have been constructed in such manner that they operate by gravitation when they are full with the determined quantity of liquid, in such manner that when said quantity is emptied into said container 38 it will descend by its own weight, carrying in its fall the rod 40 and its corresponding member 117, and thus causing the rotation of the balance-beam 106 to which it is joined by its corresponding connecting rod 114.

The reversing of this balance-beam, which is effected every time one of the transparent containers has been completely filled, transmits to the apparatus the necessary force for governing the different movements of the movable elements.

When the movable container 38 has fallen to its lower position, the fixed stem 50 causes the rising of the corresponding valve 48, in such manner that the liquid contained in same will come out through the opening 49, falling into the conduit 17 and returning to the storage tank 25 through the tube 19.

Also, when the lowering of the container 38, by the action of the excess liquid in the transparent container 7, takes place, with the corresponding rising of the opposite container 37, this will cause the rotation of the balance-beam 106 which, as may be seen in Figures 1, 2, 8 and 11, is fixed to the horizontal axle 101. The rotation of this latter axle causes the rotation of the second balance-beam 100 represented in Figures 2 and 12, which by means of the rods 98 and 99 and the chain 97, actuates the toothed wheel 95 which, as may be seen in Figures 2, 4 and 5, is intended to reverse the position of the valves 65 and 66.

It should be borne in mind that the different movements of the governing elements of the apparatus take place in three stages, which are effected during the reversion of the movable containers 37 and 38, and are as follows:—

- 45 1. Closing of the discharge valve of the transparent container to be charged.
2. Closing of the charge valve of the transparent container to be discharged.
3. Opening of the discharge valve of the transparent container to be discharged.

The first stage is effected when the toothed wheel 95 initiates its rotary movement, by means of which the axle 68 causes the rotation of the toothed pinion 82, as is shown in Figures 5 and 6, which acting on the toothed sectors 81 will rotate the arms 79 in opposite directions, causing, by means of the stems 78 the lowering of the charge valve 11 of the transparent container to be charged, that is to say, the transparent container 7, which will thus occupy the position indicated in Figure 6, having thus completed the first phase or stage of the operation. As said stems act on the center of each of the valves 16 and 77, they allow the lifting and lowering thereof in a smooth manner, thus increasing their durability.

The second stage, that is to say, the closing of the charge valve of the transparent container to be discharged, which in this case would be the transparent container 6, is effected by means of the circular sector 94 which acting by means of the notch 93 as may be seen in Figures 4 and 5, will carry in turn the piece 91 and the similar member 89. The latter, in turn, will carry the bushing 71 to which it is fixed, and this will ro-

tate the arm 67, which will cause the reversion of the valves 65 and 66. During this stage, the discharge valves 16 and 77 will not change their position, although the arms 79 are rotating.

The third stage, that is to say, the opening 5 of the discharge valve of the transparent container to be discharged, is effected every time the toothed wheel 95 ends its travel, and this operation is caused, as illustrated in Figures 5 and 6, by means of the pinion 82 and the circular 10 sector 84 which, as has been stated, is integral with the former.

The purpose of the float 165 is to lock, by means of the tooth or upper projection 168 the movement of the sector 84 while the transparent 15 container to be discharged has not been completely emptied, thus preventing a new delivery until the previous one is completed. When the liquid has finished passing through the tube 164, said float will descend and the upper projection 168 will unlock the sector 84 allowing then the corresponding reversal of the upper valve and other movable elements of the apparatus.

On the other hand, as the valves 63 and 64 25 of the transparent container to be charged remain lifted for a space approximately equal to two mm. during said charge, which is obtained by means of the balance-beams 85 and 86 illustrated in Figures 5 and 6, the excess liquid in each 30 of the transparent containers may be freely discharged up to the level of the piece 172 which, as already stated, is provided with a narrow orifice from which starts a thin overflow tube 173 discharging indirectly into the feeding tank. 35

In this manner, the excess liquid of the transparent container leaves it by said orifice, discharging in a constant manner through the said tube 173, the similar member 174, the tank 15 and the return pipe 19, the apparatus thus remaining 40 safe from any contingency.

During the second stage, the registering of the delivery is effected in the totalizer 144, and at this moment the pointer 142 indicating the quantity of liters on the disc 138, recedes into a division 45 corresponding to the five liters. This is obtained by means of the jacks 126 and 127 which, as is understood, simultaneously actuate said indicating pointer 142, and the lever 146 which acts on the totalizer 144. The second one 50 of said jacks, that is to say, the jack 127, as may be seen in Figure 11, is actuated by the balance-beam 106, when the latter operates from right to left, while the first jack, that is to say, the jack 126 is not directly operated by said balance-beam, 55 but in an indirect manner, every time said balance-beam operates from left to right. In effect, the jack 124 is moved by means of the gear 121 fixed to the axle 101, and by means of the pinion 122, the latter of which, as may be seen in the detail of Figure 14, acts on the toothed sector, formed within the disc 125, which while rotating carries said jack.

As already stated, the drum 119 is provided on its periphery with rectangular openings 120 corresponding in number to the five liter deliveries which may be effected with 50 liters, which is the maximum quantity that may be marked in one delivery. Over said openings, the free ends of the jacks 126 and 127 fit; said jacks in their dragging action will cause said drum 119 to recede with each five liter delivery, and in turn will recede the pointer 142 by the amount of the quantity indicated.

In effect, the jack 133, as may be seen in Fig- 75

ure 10, is jointed directly to the internal portion of the drum 119 and thus will be carried by same, compelling the teeth 132 to accompany same in each of their corresponding backward motions to the different five liter deliveries; on the other hand, as said teeth form a part of the bushing 128, and the latter is integral with the piece 137 and pointer 142, said pointer will effect a backward motion with each five liter delivery until it reaches zero. In the zero position, the arm 108 of the counterweight, will fit in the notch 131 of the disc 129, which is illustrated in figure 13, thus lifting again the valve 59 which will render impossible any fraudulent manipulation or delivery.

In Figure 10 it may be seen that the drum 119 in each position is retained by the lever 146, the upper end of which, ending in the form of a claw, fits in each of the openings 120 thereof; said lever, apart from acting as a retention jack for the said drum, actuates the totalizer 144. In fact, as may be seen in Figure 8, every time the upper end of said lever is raised over the drum 119, rotating about its point of articulation with the support 145, the opposite end of which the support pushes upwardly the small actuating lever of said totalizer, thus marking another unit of five liters delivered by the apparatus, said indication being perfectly visible from outside, through the opening 143 formed in the disc 138.

One of the special advantages of this type of apparatus the operation of which has been explained, resides in the elimination of all kinds of packing glands, using instead a system of valve-axes which allows a light operation.

Also, should any loss of liquid be produced along said valve-axes, same would be easily collected by the funnel 178 shown in Figures 2 and 5, and by the small tubes 177 and 174, which would discharge it into the piece 46, together with the liquid discharged by the tube 173 stated above; this liquid will come out by the narrow orifices 176 provided in the interior of said piece, to fall within the tank 15, and pass from said tank to the storage tank, through the lower tube 19.

The lubrication of the apparatus is effected by means of a suitably placed device, not shown, which insures the regular access of the lubricant to all the operating parts.

The operation in the manner explained, is quite evident and requires no further explanation to those skilled in the art.

It is evident that the invention is capable of several modifications in detail and construction, without departing from the scope of the invention as clearly set forth in the appended claims.

What is claimed is:—

1. An apparatus for supplying liquids in predetermined quantities, such as a gasoline filling pump and the like, comprising two transparent containers for the liquid to be supplied, charge valves in said transparent containers, discharge valves in said transparent containers, a system adjacent said charge valves for alternatively supplying said liquid to either of said transparent containers, a balance mechanism, means operating said balance mechanism by the overflow of the excess liquid in said transparent containers for the alternative opening and closing of said discharge valves and for the simultaneous reversal of said system, means for the simultaneous reversal of the charge and discharge valves of each of said transparent containers, means for adjusting the operation of said balance mechanism in conformity with a predetermined volume of

liquid to be delivered in each operation, means regulating the last-mentioned means in the course of the delivery of the liquid, means locking said system and the second-mentioned means in the course of the emptying of each of said transparent containers, means connected with said system for supplying said liquid thereto, the last-mentioned means comprising a general valve; means closing said general valve after a predetermined quantity of said liquid has been delivered, and means connected with said transparent containers for the expulsion of air therefrom while the transparent containers are being filled with said liquid.

2. An apparatus for supplying liquids in predetermined quantities, such as a gasoline filling pump and the like, comprising two transparent containers for the liquid to be supplied, charge valves in said transparent containers, discharge valves in said transparent containers, a system adjacent said charge valves for alternatively supplying said liquid to either of said transparent containers, two containers of predetermined capacity capable of being filled by the overflow of the excess liquid in said transparent containers, a separate jointed vertical stem connected with each of the last-mentioned containers, an auxiliary arm carrying said stems, a balance beam, said auxiliary arm being articulated upon one end of said balance beam, whereby the last-mentioned containers are suspended from said auxiliary arm and are reciprocable vertically in opposite directions by the weight of the liquid filling one of the last-mentioned containers, a registering device, a casing enclosing said registering device, a horizontal axle mounted in said device, said balance beam being fixed to said horizontal axle, a second balance beam connected with a free end of said horizontal axle and actuated thereby, a chain device connected with the second balance beam, a control axle connected with said charge valves and actuating the same, said chain device being operatively connected with said control axle and said system, whereby said system and said charge valves are actuated by the second balance beam, means for the simultaneous reversal of the charge and discharge valves of each of said transparent containers, means for adjusting the operation of said balance mechanism in conformity with a predetermined volume of liquid to be delivered in each operation, means regulating the last-mentioned means in the course of the delivery of the liquid, means locking said system and the second-mentioned means in the course of the emptying of each of said transparent containers, means connected with said system for supplying said liquid thereto, the last-mentioned means comprising a general valve; means closing said general valve after a predetermined quantity of said liquid has been delivered, and means connected with said transparent containers for the expulsion of air therefrom while the transparent containers are being filled with said liquid.

3. An apparatus for supplying liquids in predetermined quantities, such as a gasoline filling pump and the like, comprising two transparent containers for the liquid to be supplied, charge valves in said transparent containers, a double elbow conduit connected with said charge valves, discharge valves in said transparent containers, a system in said conduit for alternately supplying the liquid to either of said charge valves and said transparent containers, two containers of predetermined capacity capable of being filled by the

overflow of the excess liquid in said transparent containers, a separate jointed vertical stem connected with each of the last-mentioned containers, an auxiliary arm carrying said stems, a balance beam, said auxiliary arm being articulated upon one end of said balance beam, whereby the last-mentioned containers are suspended from said auxiliary arm and are reciprocable vertically in opposite directions by the weight of the liquid filling one of the last-mentioned containers, a registering device, a casing enclosing said registering device, a horizontal axle mounted in said casing, said balance beam being fixed to said horizontal axle, a second balance beam connected with a free end of said horizontal axle and actuated thereby, a chain device connected with the second balance beam, a control axle connected with said charge valves and actuating the same, said chain device being operatively connected with said control axle and said system, whereby said system and said charge valves are actuated by the second balance beam, a control axle connected with said charge valves and actuating the same, a chain wheel mounted upon said control axle and rotatable therewith, chain operating means connected with said chain wheel and the second balance beam, a circular sector integral with said wheel, a counterweight system, a spring pressing against said counterweight system, said sector engaging said counterweight system and actuating the same, a bushing surrounding said control axle, said counterweight system being mounted upon said bushing, a rotary arm mounted upon said axle and connected with said charge valves, whereby said charge valves are actuated by the second balance beam to admit said liquid to either of said transparent containers and permit the filling thereof, means locking the second balance beam in the course of the emptying of each of said transparent containers, means connected with said double elbow conduit for supplying said liquid thereto, the last-mentioned means comprising a general valve; means closing said general valve after a predetermined quantity of said liquid has been delivered, and means connected with said transparent containers for the expulsion of air therefrom while the transparent containers are being filled with said liquid.

4. An apparatus for supplying liquids in predetermined quantities, such as a gasoline filling pump and the like, comprising two transparent containers for the liquid to be supplied, charge valves in said transparent containers, a double elbow conduit connected with said charge valves, discharge valves in said transparent containers, a system in said conduit for alternately supplying the liquid to either of said charge valves and said transparent containers, means connected with said charge valves for alternately raising one of said charge valves to admit said liquid to either one of said transparent containers, an axle connected with the last-mentioned means, a small pinion carried by said axle, two connecting rods, sectors forming part of said connecting rods and meshing with said pinion, push stems connected with said connecting rods and said discharge valves, whereby said discharge valves are raised alternately and in synchronism with the closing of the charge valves, means connected with said double elbow conduit for supplying said liquid thereto, the last-mentioned means comprising a general valve; means closing said general valve after a predetermined quantity of said liquid has been delivered, and means connected

with said transparent containers for the expulsion of air therefrom while the transparent containers are being filled with said liquid.

5. An apparatus for supplying liquids in predetermined quantities, such as a gasoline filling pump and the like, comprising two transparent containers for the liquid to be supplied, a separate charge valve in each of said transparent containers, a separate discharge valve in each of said transparent containers, a movable balance beam, means supporting said balance beam in the middle thereof, said discharge valves being suspended from said balance beam, said charge valves being suspended from opposite ends of said balance beam, whereby the movements of the valves are carried out alternatively to each other and the movements of valves in one transparent container are carried out alternatively to the movements of the valves in the other transparent container, a system adjacent said charge valves for alternatively supplying said liquid to either of said transparent containers, means operative by the overflow of the excess liquid in said transparent containers and connected with said discharge valves and said system for the alternative opening and closing of said discharge valves and for the simultaneous reversal of said system, means for adjusting the operation of the last-mentioned means in conformity with a predetermined volume of liquid to be delivered in each operation, means regulating the last-mentioned means in the course of the delivery of the liquid, means locking said system and said balance beam in the course of the emptying of each of said transparent containers, means connected with said system for supplying said liquid thereto, the last-mentioned means comprising a general valve; means closing said general valve after a predetermined quantity of said liquid has been delivered, and means connected with said transparent containers for the expulsion of air therefrom while the transparent containers are being filled with said liquid.

6. An apparatus for supplying liquids in predetermined quantities, such as a gasoline filling pump and the like, comprising two transparent containers for the liquid to be supplied, charge valves in said transparent containers, a double elbow conduit connected with said charge valves, discharge valves in said transparent containers, a system in said conduit for alternately supplying the liquid to either of said charge valves and said transparent containers, means connected with said charge valves for alternately raising one of said charge valves to admit said liquid to either one of said transparent containers, an axle connected with the last-mentioned means, a small pinion carried by said axle, two connecting rods, sectors forming part of said connecting rods and meshing with said pinion, push stems connected with said connecting rods and said discharge valves, whereby said discharge valves are raised alternately and in synchronism with the closing of the charge valves, means connected with said double elbow conduit for supplying said liquid thereto, the last-mentioned means comprising a general valve, a hollow member connected with said transparent containers and adapted to be filled with said liquid, a float within said member, a small circular sector integral with said pinion, means connecting the last-mentioned sector with said float to lock said sector and thereby prevent the movement of said valves until said transparent containers have

been completely emptied, means closing said general valve after a predetermined quantity of said liquid has been delivered, and means connected with said transparent containers for the expulsion of air therefrom while the transparent containers are being filled with said liquid.

7. An apparatus for supplying liquids in predetermined quantities, such as a gasoline filling pump and the like, comprising two transparent containers for the liquid to be supplied, charge valves in said transparent containers, discharge valves in said transparent containers, a system adjacent said charge valves for alternatively supplying said liquid to either of said transparent containers, two containers of predetermined capacity capable of being filled by the overflow of the excess liquid in said transparent containers, a separate jointed vertical stem connected with each of the last-mentioned containers, an auxiliary arm carrying said stems, a balance beam, said auxiliary arm being articulated upon one end of said balance beam, whereby the last-mentioned containers are suspended from said auxiliary arm and are reciprocable vertically in opposite directions by the weight of the liquid filling one of the last-mentioned containers, a registering device, a casing enclosing said registering device, a horizontal axle mounted in said casing, said balance beam being fixed to said horizontal axle, a second balance beam connected with a free end of said horizontal axle and actuated thereby, a chain device connected with the second balance beam, a control axle connected with said charge valves and actuating the same, said chain device being operatively connected with said control axle and said system, whereby said system and said charge valves are actuated by the second balance beam, a circular sector integral with the first-mentioned balance beam, a jointed counterweight arm engaging said circular sector and actuated thereby, means for the simultaneous reversal of the charge and discharge valves of each of said transparent containers, means connected with said system for supplying said liquid thereto, the last-mentioned means comprising a general valve, means locking said system and the means for the simultaneous reversal of the charge and discharge valves, and means connecting said counterweight arm with the last-mentioned means and with said general valve, whereby said counterweight arm actuates said general valve and locks said charge and discharge valves after the delivery of a predetermined quantity of liquid has taken place.

55 3. An apparatus for supplying liquids in predetermined quantities, such as a gasoline filling pump and the like, comprising two transparent containers for the liquid to be supplied, charge valves in said transparent containers, discharge valves in said transparent containers, a system adjacent said charge valves for alternatively supplying said liquid to either of said transparent containers, two containers of predetermined capacity capable of being filled by the overflow of the excess liquid in said transparent containers, a separate jointed vertical stem connected with each of the last-mentioned containers, an auxiliary arm carrying said stems, a balance beam, said auxiliary arm being articulated upon one end of said balance beam, whereby the last-mentioned containers are suspended from said auxiliary arm and are reciprocable vertically in opposite directions by the weight of the liquid filling one of the last-mentioned containers, a registering device, a casing enclosing said regis-

tering device, a horizontal axle mounted in said casing, said balance beam being fixed to said horizontal axle, a second balance beam connected with a free end of said horizontal axle and actuated thereby, a chain device connected with the second balance beam, a control axle connected with said charge valves and actuating the same, said chain device being operatively connected with said control axle and said system, whereby said system and said charge valves are actuated by the second balance beam, a circular sector integral with the first-mentioned balance beam, a jointed counterweight arm engaging said circular sector and actuated thereby, means for the simultaneous reversal of the charge and discharge valves of each of said transparent containers, means connected with said system for supplying said liquid thereto, the last-mentioned means comprising a general valve, means locking said system and the means for the simultaneous reversal of the charge and discharge valves, and means connecting said counterweight arm with the last-mentioned means and with said general valve, whereby said counterweight arm actuates said general valve and locks said charge and discharge valves after the delivery of a predetermined quantity of liquid has taken place, a rod connected with one end of said counterweight arm, and a balance beam integral with said rod and engaging the lower part of said general valve, whereby said general valve on being raised to its uppermost position obstructs the admission of liquid to the two transparent containers.

9. In an apparatus for supplying liquids, a totalizer having visible numbers registering the total quantity of the delivered liquid and provided with an arm, an elbow cam periodically operating said arm and having a tooth, a circular drum having perforations formed on the periphery thereof, said tooth projecting into said perforations, and means for actuating said circular drum in conformity with the amount of the delivered liquid.

10. An apparatus for supplying liquids in predetermined quantities, such as a gasoline filling pump and the like, comprising two transparent containers for the liquid to be supplied, charge valves in said transparent containers, discharge valves in said transparent containers, a system adjacent said charge valves for alternatively supplying said liquid to either of said transparent containers, a balance mechanism, means operating said balance mechanism by the overflow of the excess liquid in said transparent containers for the alternative opening and closing of said discharge valves and for the simultaneous reversal of said system, means for the simultaneous reversal of the charge and discharge valves of each of said transparent containers, means for adjusting the operation of said balance mechanism in conformity with a predetermined volume of liquid to be delivered in each operation, means regulating the last-mentioned means in the course of the delivery of the liquid, means locking said system and the second-mentioned means in the course of the emptying of each of said transparent containers, means connected with said system for supplying said liquid thereto, the last-mentioned means comprising a general valve; means closing said general valve after a predetermined quantity of said liquid has been delivered, a cover plate closing said transparent containers, a tubular piece having one end hermetically fixed to the central portion of said

cover plate, the lower end of said tubular piece being connected with the first-mentioned means, a plug hermetically screwed to the upper portion of said tubular piece, a short tube carried by 5 said plug and concentric in relation to said tubular piece, said plug having a chamber formed therein which is in communication with the last-mentioned tube, two concentric annular chambers formed between said cover plate and said tubular 10 piece and between said tubular piece and said plug, means forming at least one conduit interconnecting said annular chambers, an exhaust tube having an upper end connected with the last-mentioned means, and a plate supporting 15 said transparent containers, the lower end of said exhaust tube being connected with the last-mentioned plate, said tubular piece having openings formed therein for the free passage of air from the interior of the transparent containers to said 20 exhaust tube.

11. An apparatus for supplying liquids in predetermined quantities, such as a gasoline filling pump and the like, comprising two transparent 25 containers for the liquid to be supplied, charge valves in said transparent containers, discharge valves in said transparent containers, a system adjacent said charge valves for alternatively supplying said liquid to either of said transparent containers, two containers of predetermined capacity capable of being filled by the overflow of 30 the excess liquid in said transparent containers, a separate jointed vertical stem connected with each of the last-mentioned containers, an auxiliary arm carrying said stems, a balance beam, 35 said auxiliary arm being articulated upon one end of said balance beam, whereby the last-mentioned containers are suspended from said auxiliary arm and are reciprocable vertically in opposite directions by the weight of the liquid filling one of 40 the last-mentioned containers, a registering device, a casing enclosing said registering device, a horizontal axle mounted in said casing, said balance beam being fixed to said horizontal axle, a second balance beam, connected with a free end 45 of said horizontal axle and actuated thereby, a chain device connected with the second balance beam, a control axle connected with said charge valves and actuating the same, said chain device being operatively connected with said control axle and said system, whereby said system and said 50 charge valves are actuated by the second balance beam, a circular sector integral with the first-mentioned balance beam, a jointed counterweight arm engaging said circular sector and actuated thereby, means for the simultaneous reversal of the charge and discharge valves of each of said 55 transparent containers, means connected with said system for supplying said liquid thereto, the last-mentioned means comprising a general valve, a rotatable curved disc having notches and teeth 60 a rotatable curved disc having notches and teeth

adapted to abut against said counterweight arm and actuate the same, and means connecting said counterweight arm with said general valve, whereby said curved disc allows the opening of said general valve to transmit said liquid to the 5 transparent containers or locks said general valve in its closed position.

12. An apparatus for supplying liquids in predetermined quantities, such as a gasoline filling pump and the like, comprising two transparent 10 containers for the liquid to be supplied, charge valves in said transparent containers, discharge valves in said transparent containers, a system adjacent said charge valves for alternatively supplying said liquid to either of said transparent 15 containers, two containers of predetermined capacity capable of being filled by the overflow of the excess liquid in said transparent containers, a separate jointed vertical stem connected with each of the last-mentioned containers, an auxiliary arm carrying said stems, a balance beam, 20 said auxiliary arm being articulated upon one end of said balance beam, whereby the last-mentioned containers are suspended from said auxiliary arm and are reciprocable vertically in opposite directions by the weight of the liquid filling one of the last-mentioned containers, a registering device, a horizontal axle mounted in said casing, 25 said balance beam being fixed to said horizontal axle, a second balance beam connected with a free end of said horizontal axle and actuated thereby, a chain device connected with the second balance beam, a control axle connected with said charge valves and actuating the same, said chain device being operatively connected with said control axle and said system, whereby said system and said charge valves are actuated by the second balance beam, a circular sector integral with the first-mentioned balance beam, a jointed counterweight arm engaging said circular sector and actuated thereby, means for the simultaneous reversal of the charge and discharge valves of each of said transparent containers, means connected with said system for supplying said liquid thereto, the last-mentioned means comprising a general valve, a rotatable curved disc having notches and teeth 30 adapted to abut against said counterweight arm and actuate the same, and means connecting said counterweight arm with said general valve, whereby said curved disc allows the opening of said general valve to transmit said liquid to the transparent containers or locks said general valve in its closed position, a pointer indicating the amounts of liquid to be delivered, 35 a member rotatable by means of a tubular key and connected with said disc, and means preventing the rotation of said member in more than one direction.

SOCRATES BAIESI. 60
